UNITED STATES PATENT OFFICE.

REINHARD HILDEBRAND, OF WEBSTER GROVES, MISSOURI.

TWO-CYCLE INTERNAL-COMBUSTION ENGINE.

Application filed May 25, 1925. Serial No. 32,586.

This invention relates generally to internal combustion engines, and particularly to a two-cycle internal combustion engine of the loop scavenging type in which scavenging ports and exhaust ports are arranged in the wall of the cylinder of said engine in proximity to each other, the main object of the invention being to produce a two-cycle engine having ports so arranged that the efficiency of the engine is increased.

Prior to this invention engines of the general type of the one disclosed herein and which were provided with scavenging and exhaust ports in proximity to each other were produced. In one engine heretofore known the exhaust ports were arranged in a row above a row of scavenging ports with both rows of ports on the same side of the cylinder, and in another make of engine the exhaust and scavenging ports were arranged on opposite sides of the cylinder. There are certain disadvantages in connection with the port arrangements of the engine just referred to, for it is plain in the case of the engine having the scavenging ports and the exhaust ports arranged in rows one above the other that the effective stroke of the piston would be reduced because of the fact that a comparatively large portion of the stroke of said piston would be required to control the ports. In connection with the engine having the scavenging and exhaust ports in opposite sides of the cylinder said ports were arranged in a row which extended almost entirely around the whole circumference of the cylinder of the engine, and as a result an opportunity was presented for the scavenging air to "short circuit" without describing a loop-like path through the entire cylinder as desired. Also, this arrangement of the ports made it difficult to employ a sufficient number of ports.

In the engine disclosed in the present application the scavenging and exhaust ports are so arranged relative to each other that the port space in a direction lengthwise of the cylinder is much less than was the port space in the engine having scavenging ports and exhaust ports arranged one above the other, and as a result of this fact the effective stroke of the piston of the engine is relatively longer. Also, the port arrangement shown herein is such and the ports are so

shaped that the circumferential port space is much less than the circumferential port space of the engine having scavenging and exhaust ports arranged on opposite sides of the cylinder, and consequently more efficient and complete scavenging of the cylinder is obtained. In addition to the foregoing, the arrangement of the ports of my improved engine is such that scavenging air is induced to follow the desirable loop-like path through the cylinder.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

The drawing illustrates a vertical section of the upper portion of an engine made in accordance with my invention.

To illustrate one embodiment of my invention, I have shown in the drawing a single acting two-cycle engine of the Diesel type, which comprises a cylinder C having an inner wall 1 and an outer wall 2 with a space 3 therebetween through which cooling fluid is caused to circulate. 4 designates a cylinder cover by means of which the upper end of the cylinder is closed, said cover being secured in place on the cylinder by means of suitable fastening devices, such as bolts 5, and being provided with a space 6 through which cooling fluid passes. The cooling fluid enters the space 3 through the inlet passageway 7 at the lower end of the cylinder and passes from said space 3 through the aperture 8 into the annular space 9 at the upper end of said cylinder. Said cooling fluid then passes from said annular space 9 through the passageway 10 into the space 6 in the cover 4 and from said space 6 through the discharge conductor 11. It is, of course, apparent that a pump will be employed to cause the cooling fluid to circulate as described, but as said pump forms no part of the present invention I have not shown the same in the drawing.

P designates the piston of my improved

engine which may be of any desirable type, the particular piston shown in the drawing being provided with a piston rod 12 rigidly fixed thereto, which piston rod is connected 5 in the usual manner to the crank shaft of the engine (not shown).

In the Diesel type of internal combustion engine liquid fuel is introduced into the combustion chamber of the engine in the form of 10 a spray, said injection of fuel taking place after the exhaust ports of the engine have been closed and after the air within the combustion chamber has been compressed, and because of the high temperature of the compressed air combustion takes place as soon as 15 the fuel contacts with the hot compressed air. In the drawing, N designates the nozzle of the engine illustrated there, and by means of which liquid fuel is sprayed into 20 the combustion chamber of said engine, said nozzle being located at the upper end of said combustion chamber and being supported by the cylinder cover 4.

In the drawing 13 designates the inlet 25 ports of my improved engine which are located in a horizontal row arranged circumferentially of the combustion chamber of the engine at a point adjacent to the lower end thereof, said row of ports extending only a 30 portion of the distance around the combustion chamber and the remainder of the inner wall of said combustion chamber being imperforate. The inlet ports are in communication with a passageway or passageways 14, 35 which extend through the wall of the cylinder and by means of which air is passed through said ports into the combustion chamber of the engine. In engines of the type illustrated in the drawing air is forced 40 under pressure through the passageway or passageways 14 and through the inlet ports 13 into the combustion chamber, but as the means for introducing said air into the combustion chamber is well known, I have not 45 shown same in the drawing. By referring to the drawing it will be seen that the inlet ports are each tapering in shape with the smaller portions of said ports at the top.

15 designates the exhaust ports of the engine which, like the inlet ports, are in a row 50 arranged circumferentially of the combustion chamber and are extended a portion only of the distance around said combustion chamber. The exhaust ports 15 are in 55 communication with a passageway or passageway 16, so that the products of combustion may be discharged from the combustion chamber through said ports 15 and passageway 16, said passageway or passageway 16 and said ports 15 preferably 60 (though not necessarily) being inclined downwardly. The exhaust ports are each tapering in shape, as shown in the drawing, and are arranged with the larger portions of 65 said ports at the tops thereof.

By referring to the drawing it will be seen that the row of inlet ports and the row of exhaust ports overlap each other, and also that said inlet and exhaust ports alternate with each other. Because of the tapering shapes of said inlet and exhaust ports said ports are capable of being nested, as shown in the drawing, and as a result though quite a number of comparatively wide ports are employed, the circumferential port space of the cylinder is not excessive. Also, the overlapping arrangement of the inlet and exhaust ports results in a reduced port space lengthwise of the cylinder whereby the effective stroke of the piston is increased. 80

When my improved engine is in operation the piston is forced downwardly by the combustion of the fuel within the piston chamber, and when said piston has traveled a sufficient distance the exhaust ports 15 will 85 be opened. As already stated, the larger portions of the exhaust ports 15 are at the top, and because of this fact the products of combustion are quickly discharged from the combustion chamber upon the opening of 90 said ports. The continued downward movement of the piston P of the engine after the exhaust ports 15 are opened causes the inlet ports 13 to be opened to admit scavenging air into the combustion chamber. The scavenging air contacts with the concave top face P' of the piston P, and said scavenging air is deflected thereby, as indicated by the arrows in the drawing, against the imperforate portion of the inner wall of the cylinder. 100 The air then follows the wall of the cylinder and describes the loop-like path indicated by the arrows in the drawing, pressing the burnt gases before it until said air finally escapes from the combustion chamber through the exhaust ports 15, leaving 105 said combustion chamber comparatively free from burnt gases. On the upward stroke of the piston the inlet ports 13 and the exhaust ports 15 are closed, and the air which is trapped within the combustion chamber is compressed, at which time the liquid fuel is sprayed into the combustion chamber, whereupon the combustion of the fuel takes place and the piston is again moved downwardly. 110

While I have illustrated in the drawing and described in the specification a single acting two-cycle engine, it is, of course, apparent that double acting two-cycle engines may be made which embody the details of 115 my invention.

I claim:

A two-cycle internal combustion engine of the loop scavenging type comprising a cylinder, a piston adapted to reciprocate within said cylinder, said cylinder having a plurality of exhaust ports arranged in a row, and a plurality of inlet ports arranged in a row through which scavenging air is passed into said cylinder, said rows of ports being 120 125 130

so arranged that said exhaust ports and said inlet ports overlap each other, thereby providing a double row of ports on one side of said cylinder in which said exhaust ports and said inlet ports alternate with each other, and said double row of ports being arranged circumferentially of said cylinder and being extended over a portion only of the circumference of said cylinder, the side of the cylinder wall opposite said double row of ports being closed to provide the scavenging loops. In testimony that I claim the foregoing I hereunto affix my signature.

REINHARD HILDEBRAND.
